his Attorney.

UNITED STATES PATENT OFFICE.

GEORGE C. ELVERS, OF CHICAGO, ILLINOIS.

SANITARY TOILET-SEAT COVER.

1,085,597.

Specification of Letters Patent.

Patented Feb. 3, 1914.

Application filed April 17, 1913. Serial No. 761,663.

To all whom it may concern:

Be it known that I, GEORGE C. ELVERS, a citizen of the United States, and a resident of the city of Chicago, county of Cook, and

5 State of Illinois, have invented certain new and useful Improvements in Sanitary Toilet-Seat Covers, of which the following is a specification.

10 My invention relates to sanitary covers for closets and the object of this improvement is to provide a device of the character mentioned which will be of durable construction and efficient in operation.

15 Other objects will appear hereinafter.

15 The invention consists in the combinations and arrangements of parts hereinafter described and claimed.

20 The invention will be best understood by reference to the accompanying drawing forming a part of this specification, and in which—

25 Figure 1 is a plan view of a blank used in the construction, Fig. 2 is a view, in perspective, of a tongue used in the construction, Fig. 3 is a plan view of a portion used in forming the pocket, and Fig. 4 is a central sectional view of the closet supplied with a covering embodying my invention.

30 The preferred form of construction as illustrated in the accompanying drawing comprises a sheet 5 of thin flexible material, preferably of paper having an oval perforation 6 in its center and a tongue 7 formed on one edge of the perforation 6 and extended 35 into said opening. The tongue 7 is formed integrally with the sheet 5 and cut out substantially as indicated by the full lines in

Fig. 1. A triangular piece of sheet material 8 is creased on line 9 in Fig. 3 and bent to substantially the shape indicated by the dotted lines in this figure. The tongue 7 is folded on lines 10, forming flaps 11 and 12, the flap 11 is glued to its contacting side of member 8 and flap 12 glued to its con-

40 tacting side of said member 8 with the edge portion 13 folded over and glued to the edge of flap 11 substantially as indicated in Fig. 2. This construction provides a pocket between the end portion of 45 tongue 7 and the under side of the member

8. In use, the sheet 5 is placed on the seat 14 of the closet bowl 15 with the perforation 6 registering with the perforation 16 in the seat 14. The tongue 7 extends downwardly into the bowl 15 with the pocket 17, 55 which is formed at the end of tongue 7 as above described opening upwardly and so that when the closet is flushed in the usual manner, water issuing from the perforations 18 around the top edge of bowl 15 will engage pocket 17 and draw the cover 5 into the water and permit it to be drawn downwardly through the waste 19 of the closet. The sheet 5 is placed in position manually and is preferably placed so that the pocket 60 17 is in the position indicated in Fig. 4 but may be turned with its other side up when desired. The member 8 is preferably made of more rigid material than sheet 5 in order to give the pocket 17 proper stiffness to 70 maintain it open so that water will enter it upon contacting therewith. The sheet 5 and member 8 may be made of any suitable material but paper is preferred.

75 While I have illustrated and described the preferred form of construction for carrying my invention into effect, this is capable of variation and modification without departing from the spirit of the invention. I, therefore, do not wish to be limited to the 80 precise details of construction set forth, but desire to avail myself of such variations and modifications as come within the scope of the appended claims.

Having described my invention what I 85 claim as new and desire to secure by Letters Patent is:

1. A device of the class described comprising a sheet of flexible material having a perforation therein; a tongue disposed in 90 said perforation and provided with a pocket at its free end, substantially as described.

2. A device of the class described comprising a flexible material having a perforation therein; a tongue formed integrally therewith and extending into said perforation and provided with a pocket at its free end, substantially as described. 95

3. A device of the class described com- 100

prising a sheet of flexible material having a perforation therein; a tongue formed integrally therewith and extending into said perforation; a bent sheet of material disposed at the free end of said tongue and secured thereto forming a pocket therebetween, substantially as described.

In testimony whereof I have signed my name to this specification in the presence of two subscribing witnesses.

GEORGE C. ELVERS.
